UNITED STATES PATENT OFFICE.

RUDOLF E. HELLMUND, OF PITTSBURGH, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,287,014.

Specification of Letters Patent.

Patented Dec. 10, 1918.

Application filed April 29, 1915. Serial No. 24,735.

To all whom it may concern:

Be it known that I, RUDOLF E. HELLMUND, a subject of the Emperor of Germany, and a resident of Pittsburgh, in the county of Allegheny and State of Pennsylvania, have invented a new and useful Improvement in Systems of Control, of which the following is a specification.

My invention relates to control systems for alternating-current motors of the commutating type, and it has for one of its objects to provide means whereby a motor of the character specified may be accelerated in a smooth and gradual manner with high starting torque and subsequently be operated at substantially uniform running speed, irrespective of variations in the supply voltage.

Another object of my invention is to provide means whereby a motor of the character specified may, if coupled to a suitable mechanical load, be employed to regenerate and supply power to the source with a minimum amount of special auxiliary apparatus.

Still another object of my invention is to provide a control system of the character specified wherein the ratio of the number of control switches to the number of accelerating and running positions is lower than has been customary hitherto and wherein many of the control switches carry but a small portion of the load current and need therefore be of but small size.

In the operation of electric motors of the compensated, commutating, alternating-current type it is desirable to have the apparatus connected either as a series, or as a repulsion, motor during periods of acceleration in order that large starting torque and relatively small drain upon the line shall be produced. When the motor is running at full speed, however, it is preferable to so connect it that it will have a shunt characteristic in order that the power factor may be readily controlled and that the speed may be maintained relatively constant when connected to a source of variable voltage. Furthermore, the commutation is somewhat better when operating with a shunt characteristic, and the motor may be used for regeneration with but slight change in the connections thereof. This last named feature is of great importance in electric railway systems where regeneration may be employed for braking, for decelerating or for

the equalization of the load on the line by the simultaneous dropping of the frequency and the voltage of the line. I have provided a system of motor control whereby all of the above named connections and advantages 60 may be obtained in an extremely simple and effective manner.

In the accompanying drawing, Figure 1 is a diagrammatic view of a motor with its attendant control circuits and auxiliary apparatus, illustrating one embodiment of my invention; Fig. 2 is a chart showing the sequence of switch operation in the control circuit of Fig. 1 during the entire process of acceleration; Figs. 3 to 10, inclusive, are simplified diagrammatic views illustrating the development of the connections in the system of Fig. 1; and Fig. 11 is a diagrammatic view of a modification of the system shown in Fig. 1. 75

An alternating-current motor 18 of the compensated commutating type is provided with an armature 14, a main field winding 15 and a cross field winding 16. The motor 13 is supplied with alternating current from 80 a secondary winding 17 of a transformer 18 provided with a primary winding 19 energized from any suitable alternating current line, such, for example, as a trolley wire 20. The connection between the motor 13 and 85 the secondary winding 17 may be controlled by suitable switches 1, 2, 3 and 5 and a preventive reactance device 21.

The main field winding 15 is energized, not only by current from the secondary 90 winding 17 but also by an auxiliary exciting machine 22, preferably of the short-circuited armature, phase-shifting type. Briefly stated, the machine 22 comprises an armature 23 of the commutating type with 95 its brushes short circuited, a main field winding 24, and a cross field winding 25. Driving torque may be obtained from any suitable means, such, for example, as a variable speed motor 26. Upon supplying the 100 main field winding 24 with alternating current and driving the armature 23, an alternating current will be induced in the winding 25 which will be of the same frequency as that supplied to the winding 24 but will 105 differ therefrom in voltage, depending upon the ratio between the number of turns in the windings 23, 24 and 25, and differing therefrom in phase, depending upon the position of the brushes of the armature 23 with re- 110

spect to the axes of the windings 24 and 25. The machine 22 is connected to an auxiliary secondary winding 28 on the transformer 18, and the voltage applied to the main field winding 24 may be varied by suitable switches 9, 10, 11 and 12. The voltage supplied to the main field winding 15 by the inducing winding 25 is preferably supplemented by a small voltage derived from the secondary winding 28, as indicated at the right hand end thereof for phase control. The entire auxiliary exciting circuit is controlled by a suitable switch 8.

The armature 14 may be connected or disconnected from the windings 15 and 16 by a switch 4, and the main field winding 15 may be shunted either by a resistance member 29, controlled by a suitable switch 6; or by a lower-resistance path controlled by the switch 6 and an additional switch 7.

Having thus described the arrangement of circuits for the control of the motor 13, the operation is as follows: Referring to the chart in Fig. 2, the accelerating positions are indicated in the left hand column and those of the accelerating positions, which are suitable for continuous running, are indicated by "R" in the next succeeding column. The remaining columns indicate the switches which are closed during each of the accelerating positions, as is well understood in the art. In spite of the advantages of a series or a repulsion connection, corresponding to a relatively "steep" speed-torque curve, for low-speed accelerating positions, I have found that a shunt connection, corresponding to a relatively "flat" speed-torque curve, is best for the first speed because it permits one to definitely fix the strength of the main field to give the maximum short-circuit voltage under the brushes. This shunt operating connection is obtained, as indicated, by closing the switches 1, 2, 4, 5, 8, 9 and 12. See Fig. 3. The armature 14 is short circuited by the switches 2 and 4, and the cross field winding 16 is provided with a maximum excitation by being connected across the entire winding 17. The main field winding 15 is excited solely by the auxiliary machine 22 and the portion of the secondary winding 28, giving a shunt operating characteristic to the motor 13. The excitation provided by the machine 22 is at a maximum because the main field winding 24 thereof is connected across the maximum possible portion of the secondary winding 28 through switches 9 and 12.

In order to pass to the next running position, indicated as accelerating position number 4 on the chart, wherein the switches 1, 2, 5, 6 and 7 are closed, as indicated in Fig. 4, and the main field winding 15 is excited solely by current induced in the armature 14 by the cross field winding 16, it is necessary, in order to avoid abrupt changes in the speed,

corresponding to a sudden transition from one speed-torque curve to another remotely-related curve, to transfer the excitation of the main field winding 15 from the auxiliary source to the armature 14 in a smooth and gradual manner. This result is obtained as indicated, by first closing the switch 6, connecting the resistance member 29 in shunt relation to the field winding 15, allowing a small amount of current from the armature 14 to pass through the winding 15, then opening the switch 4 so that all of the current flowing in the armature 14 is required to pass through the main field winding 15, and finally closing the switch 7 and opening the switch 8, whereby the resistance member 29 is eliminated from the circuit, the windings 14 and 15 are connected in series relation in a low-resistance loop, and the auxiliary excitation of the winding 15 is entirely removed.

While the motor 13 is thus operating solely with excitation from the source and with a series characteristic corresponding to a relatively "steep" speed-torque curve, the voltage produced by the machine 22 is lowered by reducing the excitation of the winding 24 by opening the switch 9 and closing the switch 10. This operation would entail abrupt field changes in the field 15 were said machine dependent upon the machine 22 for excitation at all times but, by performing this operation when the machine 22 is disconnected from the winding 15, such abrupt field changes are avoided.

The next running position, indicated as the seventh accelerating notch corresponding to Fig. 5, has the same connections, corresponding to a relatively "flat" speed-torque curve, as does the first running position except that the voltage produced by the machine 22 is lower than in the earlier case. The transfer to these connections is made by reversing the aforementioned method of introducing the preventive resistance 29 as will be readily apparent from the switch manipulation illustrated in connection with accelerating notches 5 and 6.

In passing to the next running position, found at the thirteenth accelerating notch corresponding to Fig. 6, wherein the connections are the same as with the seventh accelerating position except that the voltage produced by the machine 22 is still lower, owing to the transfer of connection from the switch 10 to the switch 11, the same cycles of operation are gone through with as was followed between accelerating positions 1 and 7. It should be understood that the intermediate accelerating notches, corresponding to relatively "steep" speed-torque curves, are employed only for extremely short periods, as the connections of accelerating position 10, for example, are identical with those of accelerating position

4 and there would be a reversion to the speed of position 4 were the connections of position 10 maintained for an appreciable period of time.

5 Between the two running positions indicated at the thirteenth and eighteenth accelerating positions, corresponding to Fig. 6 and to Fig. 7, respectively, an increase in speed is obtained by raising the voltage applied to the armature 14 through the closing of the switch 3 and the opening of the switch 2. In the seventeenth acceleration position, the switches 2 and 3 are both closed but short circuiting of the attendant portion of the secondary winding 17 is prevented by the action of the preventive-resistance device 21. During the seventeenth, and all subsequent accelerating positions, the armature 14 is energized from the cross field winding 16 and also by direct-current flow from the winding 17, thus producing the well known doubly-fed connection for motors of this type. It will be noted that, by the establishment of an intermediate connection through the voltage 3, the voltage applied to the cross field winding 16 will be less than has hitherto been the case, but the consequent reduction of current induced in the armature 14 will be compensated for by the additional direct flow from the winding 17. During the sixteenth, seventeenth and eighteenth accelerating positions, the machine 13 is self-exciting with a series characteristic, and advantage is taken of this period for raising the voltage of the machine 22 to a maximum value through opening the switch 11 and closing the switch 9, so that, when the twentieth accelerating position is reached, connections are exactly the same as in the second accelerating position, with the exception that current flow has been introduced through the switch 3 and discontinued through the switch 2. From this point, acceleration is produced by following the same cycles of operation as were employed in the lower accelerating stages, gradually reducing the voltage provided by the machine 22 and preventing abrupt changes in the excitation of the machine 13 through suitable manipulation of the switches 4, 6 and 7 and the preventive-resistance device 29. The simplified Figs. 8, 9 and 10, respectively representing conditions at the remaining running notches, namely, numbers 22, 26 and 30, thus correspond to Figs. 3, 5 and 6, respectively.

If desired, extremely gradual changes in the field 13 may be obtained by varying the speed of the machine 22 by controlling the speed of the driving motor thereof, as, for example, by a suitable rheostat connected in circuit with the auxiliary motor 26.

An extension of the above described method of control is shown in Fig. 11 where-
65 in the main field winding of the phase con-

verter 22 has a substantially constant excitation from the source, and the control switches 9, 10 and 11 are transferred to the circuit of the driving motor 26, shown, in this case, as of the repulsion type. The manipulation of the switches is the same as in the circuit of Fig. 1, the voltage of the machine 22 being raised by increasing the speed thereof rather than by increasing the main field excitation. A fly-wheel 27 on the shaft of the machine 22 prevents abrupt changes in the speed and, therefore, in the voltage of the exciting current supplied to the machine 13.

By the systems of connections shown, I am enabled to obtain eight running positions, with a large number of intermediate accelerating positions, by the use of but twelve switches, many of which carry but small current, but it is necessary for me to revert to the series operating connections when adjusting the voltage of the machine 22. I may, if desired, avoid this necessity by providing suitable preventive-resistance or reactive members at the switches 9, 10 and 11, as is well known in the art, but to do so would entail additional switches with their attendant disadvantages.

While I have illustrated my invention in its preferred form, it will be obvious to those skilled in the art that it is susceptible of various minor changes and modifications without departing from the spirit thereof, and I desire, therefore, that only such limitations shall be placed thereupon as are imposed by the prior art or are set forth in the appended claims.

I claim as my invention:

1. The method of accelerating an alternating-current commutator motor provided with both magnetizing and inducing-field windings, said motor being associated with a main source of alternating current and an auxiliary source of current, dephased with respect to said main source, and being provided with means for energizing said inducing-field winding directly from said main source, means for short-circuiting the armature winding, means for forming a closed circuit through said armature winding and said magnetizing-field winding, and means for jointly exciting said magnetizing-field winding from said main source and from adjustable portions of said auxiliary source, which comprises initially connecting said inducing-field winding across a portion of said main source, short-circuiting said armature winding, connecting said magnetizing-field winding to be jointly energized by a portion of said main source and by a relatively large portion of said auxiliary source, and thereafter accelerating said motor by decreasing the component of the magnetizing-field energization derived from said auxiliary source, closing a circuit from

4
said armature winding through said magnetizing-field winding during transition periods in the adjustment of said component voltage.

5 2. The method of accelerating an alternating-current commutator motor provided with both magnetizing and inducing-field windings, said motor being associated with a main source of alternating current and an auxiliary source of current, dephased with respect to said main source, and being provided with means for energizing said inducing-field winding from a portion of said source through an impedance device, means 10 for energizing the armature winding from an adjacent portion of said source through said impedance device, means for inserting said magnetizing-field winding in said armature-exciting circuit, and means for connecting said magnetizing-field winding to be energized jointly by a portion of said main source and by said auxiliary source, which comprises initially connecting said inducing-field winding and armature windings to said main source through said impedance device, while including said magnetizing-field winding in said armature-exciting circuit, transferring said magnetizing-field winding to said joint exciting circuit with said dephased component at a relatively large value, and then decreasing the value of said dephased component.

3. The method of accelerating an alternating-current commutator motor provided with both magnetizing and inducing-field windings, said motor being associated with a main source of alternating current and an auxiliary source of current, dephased with respect to said main source, and being provided with means for energizing said inducing-field winding from a portion of said source, means for energizing the armature winding from an adjacent portion of said source, means for inserting said magnetizing-field winding in said armature-exciting circuit, and means for connecting said magnetizing-field winding to be energized jointly by a portion of said main source and by said auxiliary source, which comprises initially connecting said inducing-field winding and armature windings to said main source while including said magnetizing-field winding in said armature-exciting circuit, transferring said magnetizing-field winding to said joint exciting circuit with said dephased component at a relatively large value, and then decreasing the value of said dephased component.

4. The method of accelerating an alternating-current commutator motor provided with both magnetizing and inducing-field windings, said motor being associated with a main source of alternating current and an auxiliary source of current, dephased with respect to said main source, and being pro-

vided with means for energizing said inducing-field winding directly from a major or a minor portion of said main source, means for short-circuiting the armature winding 70 means for connecting said armature winding across a portion of said main source and means for jointly exciting said magnetizing-field winding from said main source and from adjustable portions of said auxiliary source which comprises initially connecting 75 said inducing-field winding across a portion of said main source, short-circuiting said armature winding, connecting said magnetizing-field winding to be jointly energized by a portion of said main source and 80 by a relatively large portion of said auxiliary source, accelerating said motor by decreasing said dephased component of the magnetizing field energization, transferring to a connection wherein 85 the armature and inducing-field windings are both connected across portions of said main source and said magnetizing-field winding is energized by said joint excitation with the dephased component at a maximum, and thereafter decreasing said dephased component of the magnetizing-field excitation.

5. The method of accelerating an alternating-current commutator motor provided with both magnetizing and inducing-field windings, said motor being associated with a main source of alternating current and an auxiliary source of current, dephased with respect to said main source, and being provided with means for energizing said inducing-field winding directly from a major or a minor portion of said main source, including an impedance device in series with 100 said inducing-field winding when connected across the minor portion of said source, means for short-circuiting the armature winding, means for connecting said armature winding across a portion of said main source through said impedance device, and means for jointly exciting said magnetizing-field winding from said main source and from adjustable portions of said auxiliary source which comprises initially connecting 105 said inducing-field winding across a portion of said main source, short-circuiting said armature winding, connecting said magnetizing-field winding to be jointly energized by a portion of said main source and by a relatively large portion of said auxiliary 110 source, accelerating said motor by decreasing said dephased component of the magnetizing field energization, transferring to a connection wherein the armature and inducing-field windings are both connected across portions of said main source through said impedance device and said magnetizing-field winding is energized by said joint excitation with the dephased component at a maximum, and thereafter decreasing said de- 115

120
125
130

phased component of the magnetizing-field excitation.

6. The method of accelerating an alternating-current commutator motor provided with both magnetizing and inducing-field windings, said motor being associated with a main source of alternating current and an auxiliary source of current, dephased with respect to said main source, and being provided with means for energizing said inducing-field winding directly from a major or a minor portion of said main source, means for short-circuiting the armature winding, means for including said magnetizing-field winding in said armature short-circuit, means for connecting said armature winding across a portion of said main source, and means for jointly exciting said magnetizing-field winding from said main source and from adjustable portions of said auxiliary source which comprises initially connecting said inducing-field winding across a portion of said main source, short-circuiting said armature winding, connecting said magnetizing field winding to be jointly energized by a portion of said main source and by a relatively large portion of said auxiliary source, accelerating said motor by decreasing said dephased component of the magnetizing field energization, inserting said magnetizing-field winding in the armature short-circuit during transition periods of said dephased exciting component, transferring to a connection wherein the armature and inducing-field windings are both connected across portions of said main source and said magnetizing-field winding is energized by said joint excitation with the dephased component at a maxi-

mum, and thereafter decreasing said dephased component of the magnetizing-field excitation.

7. The method of accelerating an alternating-current commutator motor having both magnetizing and inducing field windings in conjunction with a main source of energy and an auxiliary source of current dephased from said main source which comprises initially and at predetermined subsequent intervals connecting said sources to said magnetizing field winding to produce a shunt characteristic, exciting said magnetizing field winding in accordance with the motor load during intermediate operating conditions, and gradually decreasing the component of the magnetizing-field-winding energization derived from said auxiliary source.

8. The method of operating an electric motor of the commutator type having a magnetizing field winding in conjunction with a main source of energy and an auxiliary source of current which comprises connecting said auxiliary source to said magnetizing field winding together with the main source so as to produce a relatively "flat" speed-torque characteristic, subsequently exciting said magnetizing field winding substantially in accordance with the motor load, again connecting the main and the auxiliary sources in circuit, and then gradually varying the magnetizing-field energization derived from said auxiliary source.

In testimony whereof, I have hereunto subscribed my name this 23rd day of April 75
1915.

RUDOLF E. HELLMUND.
